UNITED STATES PATENT OFFICE.

ALBERT M. JOHNSON, OF ROCKFORD, ILLINOIS, ASSIGNOR TO BARNES DRILL COMPANY, OF ROCKFORD, ILLINOIS, A CORPORATION OF ILLINOIS.

FEED MECHANISM FOR DRILLING MACHINES.

Application filed January 24, 1925. Serial No. 4,373.

The invention relates in general to drilling machines and has especial reference to the means for feeding the tool spindle to the work.

5 Machines of this character are usually driven by an electric motor operated at a high speed and in order that such a source of power may be used in feeding the cutting tool or tools to the work it is necessary to 10 provide for a large reduction in the speed of the gear element acting on the tool spindle. Heretofore it has been the practice to employ reduction gearing including a worm and worm wheel to obtain the necessary 15 speed reduction. Considerable difficulty has been experienced, however, with this worm gear reduction because it is unable to withstand for any substantial length of time the heavy wear to which it is subjected and consequently must frequently be replaced causing 20 annoyance and expense.

The object of my invention generally stated is to provide a feed mechanism dispensing with the worm gear reduction referred to and utilizing a novel and advantageous spur gear reduction capable of effectually overcoming the difficulty referred to.

In the accompanying drawings wherein 30 I have illustrated my improved feed mechanism in its preferred form, Figure 1 is a fragmentary side elevational view of a drilling machine embodying the invention.

Fig. 2 is a fragmentary horizontal sectional view taken approximately in the plane of line 2—2 of Fig. 1.

Fig. 3 is a vertical sectional view taken approximately in the plane of line 3—3 of Fig. 2.

40 The drilling machine selected for purposes of illustration comprises an upright standard 7 having mounted on its forward side a bracket 8 for vertical adjustment, the adjusting means being of any suitable character. The bracket 8 carries at its forward end a tubular head 9 in which the sleeve 10 of the tool spindle 11 is mounted for up and down sliding movements. The sleeve as usual is held against longitudinal movement 45 on the spindle 11 by suitable and well known means and is equipped on its rear side with a rack 12.

Projecting upwardly and forwardly from the standard 7 is a housing 13 enclosing a 50 driven shaft 14 which may be connected with

the source of power in the usual or any preferred way. A forward extension 15 of the housing 13 serves to enclose a crown gear 16 with which a bevel pinion 17 on the upper end of the shaft 14 is constantly in mesh. 60 The gear 16 is splined on the upper end of the tool spindle 11 so as to impart rotation thereto.

A vertical shaft 20 disposed rearwardly of the tool spindle 11 is journaled at its lower end in a bracket 21 supported by the standard 7 at one side of the bracket 8. At its upper end this shaft is journaled in a gear box 22, and has a clutch 23 interposed therein in the box. The shaft 20 is driven 70 through change speed gearing 24 in the gear box 22 subject to suitable manual control. The construction of this gearing 24 may be of any preferred character, that herein shown being adapted to effect eight changes 75 in speed. A driving connection between the spindle and the reduction gearing is provided by a pair of spur gears 25, the same being herein enclosed in a housing 25a.

The lower end of the shaft 20 has a bevel 80 pinion 26 thereon meshing with a bevel gear 27 journaled on a stud shaft 28 which is carried by the bracket 8 (Fig. 2). Rigid with the gear 27 is a spur pinion 29 meshing with a spur gear 30 which is journaled on 85 a short shaft 31 mounted for movement about the axis of the shaft 28. Herein the short shaft 31 is journaled in a bifurcated arm 32 (Fig. 2) which is pivoted on the stud shaft 28 and extends forwardly to one 90 side of the head 9. The shaft 31 also has rigid therewith a spur pinion 33 meshing with a spur gear 34 on a counter-shaft 35 journaled in and extending through the bracket 8. On the side of the bracket 8 opposite the gear 34 the shaft 35 carries a pinion 36 meshing with a spur gear element 37 in the form of an annular member or hollow drum provided with internal gear teeth as shown in Fig. 3. This drum is fast upon a feed shaft 38 also journaled in the bracket 8 carrying a pinion 39 located in a slot in the bracket and meshing with the rack 12. 95

In the operation of feeding the spindle 105 downwardly, the arm 32 is supported by a latch device 40 in an elevated position in which the pinion 33 meshes with the spur gear 34 so that power communicated from the spindle 11 through the gears 25 and 110

change speed gearing 24 is transmitted through the shaft 20, the bevel gearing 26, 27 and the spur gear train 29, 30, 33, 34, 36, 37 and 39 to the rack 12; this train providing five distinct reductions in speed.

It will be seen that by dividing the gear train 29, 30, etc., arranging a portion thereof on one side of the bracket 8 and a portion on the opposite side, I obtain a desirable 10 compactness in the arrangement of the parts while providing the necessary reduction in speed by means of spur gearing, thus greatly increasing the life of the feed mechanism.

On the end of the countershaft opposite 15 the drum, I provide a star wheel consisting of a hub 40 and a plurality of radial arms or hand levers 41. Said star wheel is adapted for use in feeding the spindle to the work manually, when the power means is 20 disengaged. It will be seen that through the gearing connection provided by the internal gear drum and the feed shaft it is possible to multiply greatly the power applied to the star wheel handle for feeding 25 the spindle.

I claim as my invention:

A drilling machine comprising, in combination, an upright frame having an arm extending forwardly therefrom, a head on

said arm, a spindle having a sleeve held 30 against endwise movement thereon and mounted for up and down movement in said head, a rack on said sleeve, a cross feed shaft journaled in said arm and having a pinion meshing with said rack, said cross feed shaft extending to one side of said arm and having an internal spur gear in driving relation thereto, a second shaft mounted in said arm in parallel relation to the cross feed shaft and having a pinion on one end 35 meshing with said internal gear, the other end of said second shaft having a spur gear on the opposite side of said arm, a spur pinion, a pivotal support whereby said spur pinion is mounted for movement into and 40 out of mesh with said last mentioned spur gear, a pair of intermeshing spur gears carried by said support, one of which gears is rigid with said spur pinion and the other 45 of which has its axis coaxial with the pivotal axis of the support, a power driven shaft, and speed reduction gearing providing a driving connection between said power driven shaft and the gear in axial relation to the pivotal support. 50

In testimony whereof, I have hereunto affixed my signature.

ALBERT M. JOHNSON.
